The ornamental design for a vehicle bumper, as shown and described.

DESCRIPTION

FIG. 1 is a front upper perspective view of a vehicle bumper showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines formed of equal-sized dashes show portions of the vehicle bumper which form no part of the claimed design.

The broken lines formed of alternating long and short dashes define the bounds of the claimed design and form no part thereof.
